CLAIM

The ornamental design for a rooftop tent for vehicle, as shown and described.

DESCRIPTION

FIG. 1 is a front perspective view of a rooftop tent for vehicle showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of a portion indicated with “9” in FIG. 1.

FIG. 10 is an enlarged view of a portion indicated with “10” in FIG. 1.

FIG. 11 is an enlarged view of a portion indicated with “11” in FIG. 2; and,

FIG. 12 is an enlarged view of a portion indicated with “12” in FIG. 2.

The broken lines illustrate portions of the rooftop tent for vehicle that form no part of the claimed design. The dot-dash broken lines in FIGS. 1, 2, and 9-12 are included to show a partially enlarged view only and form no part of the claimed design.
